UNITED STATES PATENT OFFICE.

BERNARD J. HAUSFELD AND EDMUND H. LUNKEN, OF CINCINNATI, OHIO;
SAID HAUSFELD ASSIGNOR TO SAID LUNKEN.

WINDOW CONSTRUCTION.

SPECIFICATION forming part of Letters Patent No. 760,626, dated May 24, 1904.

Application filed January 8, 1904. Serial No. 188,199. (No model.)

To all whom it may concern:

Be it known that we, BERNARD J. HAUSFELD and EDMUND H. LUNKEN, citizens of the United States, residing at Cincinnati, Ohio, have invented certain new and useful Improvements in Window Constructions, of which the following is a specification.

Our present invention relates to window constructions for buildings of the general style disclosed in applications for Letters Patent of the United States filed by us September 14, 1903, Serial No. 173,118, and November 27, 1903, Serial No. 182,860; and it consists in various improved features and in the construction and arrangement of parts, as will be hereinafter described, and particularly pointed out in the claims.

In the accompanying drawings, Figure 1 shows in perspective a window embodying our present improvements and having its secondary or sash-carrying frame arranged to swing about horizontally-disposed pivots. Fig. 2 is a similar view of a window in which the secondary frame moves about vertical pivots, our invention being susceptible of embodiment in this form of window as well as in that shown in Fig. 1. Fig. 3 is a horizontal sectional view through a window embodying our invention and illustrated in Fig. 2, the screen-grooves being omitted. Fig. 4 is a vertical sectional view of the window illustrated in Fig. 2, taken to one side of the axis of the hinge. Figs. 5 and 6 are detail views showing how the sashes may be arranged to counterbalance each other by gearing interposed between them. Fig. 5^a is a detail view of the means for supporting the balancing-pinion. Fig. 7 is a detail perspective view relating to the hinge stop-strips. Fig. 8 is a detail sectional view illustrating the improved construction and arrangement of pivot and its relation to the stop-strips. Figs. 9 and 10 are detail views relating to the pivot connection between the secondary and the main frame. Fig. 11 is a perspective view of the hinge stop-strips and their continuations along the adjacent sides of the window member to which they are attached. Fig. 12 is a detail view of the closing or covering strip composed of the rigid

and hinged section. Figs. 13 and 14 are perspective views relating to means for weight-ing the sashes and the sash carrying or swing-ing frames.

In the drawings, 1 indicates the main frame, which may be fixed in the window-opening in any suitable manner—such, for instance, as is disclosed in our application, Serial No. 182,860, above referred to, in which said main frame is placed in a casing located within the window-opening.

In our present invention we retain the principal features of the stop mechanism disclosed in the applications above mentioned—namely, the strips extending on each side of the pivots and projecting unequally into the window-opening, so that the stops of less pro-jection may pass one over the other in swing-ing the window through a half-revolution.

One feature of our present invention relates to means for closing the groove or space on the inner side of the window lying between the main frame 1 and the secondary pivoted frame 2, so that a practically flush surface will be presented, a finished appearance will be produced, and the main frame and the swinging frame will appear as one and without any dividing space between them so long as the swinging frame is in normal position in the main frame.

Referring to Fig. 1, it will be seen that we provide a closing or finishing strip 3 along the bottom of the opening in the main frame, and this effect is continued by a strip extending up on either side of the main frame, as at 3', to the point 3'', which is slightly below the horizontal plane of the pivots of the secondary frame and which are indicated generally at the points 4. At the points 3'' additional closing-strips 5 are provided; but, unlike the strips 3', they are pivotally supported in the main frame, as clearly indicated in Fig. 1, the pivots being either directly on the main frame or on the fixed closing-strip 3' of angular form, Fig. 12, and attached to said main frame. These pivoted covering or clos-ing strips are preferably of angle-iron, one flange, 5', being adapted to lie along the side edge of the secondary frame and the other

flange, 5", extending from the secondary frame to the inner edge of the main frame and substantially in the plane of the inner face of the secondary or swinging frame when in normal position, and thus covering the space which exists between the edge of the secondary frame and the main frame. As will be observed from Fig. 1, the closing or covering strips are arranged at the front of the window-opening, and therefore their pivots are out of the axial line of the journals of the secondary swinging frame, and, further, they are arranged in a lower plane than the said journals. In order to allow this arrangement of the pivoted closing-strips, we provide sliding connections between the upper ends of the same and the upper ends of the secondary frame, formed by slots 6 in the strips through which bolts or pins pass to hold the strips movably to the edge of the secondary frame. As the secondary frame swings on its trunnions the pivoted sections 5 of the covering-strips will move therewith while maintaining their connections with said secondary frames, and the latter may move through substantially a half-revolution, the pivotal and sliding connections just described allowing this to be accomplished without interference on the part of the covering-strips. This closing-strip is also used in the form of window shown in Fig. 2, wherein the secondary frame moves about vertically-disposed pivots. In this arrangement the fixed part of the closing-strip extends up one side 3" and across the top and bottom of the window to near the middle of the swinging frame, where the hinged sections 5" of the covering-strips are pivoted to the main frame in a manner similar to that described above. These hinged closing or covering strips, which extend horizontally, are connected at their free ends to the swinging frame by means of pin-and-slot connections like those described above. It will be seen that in both forms of construction the same result is secured by the fixed and hinged covering-strips—that is to say, covering or closing from view the space or groove located between the edge of the swinging frame and the main frame. The closing or covering strips 3" in Fig. 2 are combined, as shown in Fig. 3, with stop-strips 6", being formed in one piece therewith and of rolled metal. This piece of metal (marked 7) carrying the two strips is secured in place by rivets 8, as shown, to the main frame, or when the said rolled pieces are carried by the swinging part of the window they are secured thereto as shown at 6". The same construction—*i. e.*, combining the closing and stop strips on one piece of material—is used in connection with the closing-strip 3 of Fig. 1. In each case the stop flange or strip is located at one edge of the rolled piece 7 and the closing flange or strip at the other edge thereof. The stop-flanges coöperate with packed stop-strips 9 9", composed of channel-iron pieces

secured to the fixed or movable frame, as the case may be and as illustrated in Fig. 3.

Referring now to the manner of hinging or pivotally supporting the swinging frame and to the particular construction and arrangement of the stop-strips of unequal projection which are associated with the said hinge, it will be observed from Figs. 7 and 8 that the pivot-trunnion and the socket are arranged independent of the stop-strips. These stop-strips we will designate as the "hinge" stop-strips for convenience in distinguishing them from those formerly described and which are associated or coöperate with the free edges of the swinging frame. In Figs. 3, 7, and 11, 9" indicates the hinge stop-strip which is secured to the main frame and 10 the hinge stop-strip which is carried by the swinging frame. Each of these stop-strips is composed of a high part marked 9' and 10', respectively, and each has also a low part 9" and 10", and, as in the applications above mentioned, the low parts or those of least projection into the window-opening are adapted to engage with the high parts or those parts of greatest projection into the window-opening, as shown in Fig. 4, and when the secondary frame is swung on its pivots the part 10" of least projection can ride over the low part 9" of the other stop-strip. Each of the hinge stop-strips is of channel form, substantially U shape in cross-section; but the channel of the high part faces in the opposite direction from the channel in the low part of the same strip. The low parts carry packing 11 in their channels to contact with the narrow flanges 12 of the high parts of the opposing stop-strip. Each high part of the hinge stop-strips is provided with a closing or covering flange 13, which serves to cover or close the space left between the low part of either hinge stop-strip and the opposing member of the window.

As shown in Fig. 7, we form each hinge stop-strip in sections, which are united by a block 12' of right-angular form, fixed by rivets 12" in the channel of the high section and extending also into the channel in the low section, where it is also riveted. The side face of the block is covered with suitable packing or buffer material 14, which prevents contact between the metal surfaces of the fixed and movable stop-strips at this point and forms a tight joint when the swinging frame is in closed position.

We prefer to form the hinge stop-strips—*i. e.*, those adjacent the hinge—together with those extending along the adjacent sides of the window—all of one piece. This is illustrated in Fig. 11, where it will be noticed, for instance, that the channel-iron stop-strips 9 are formed of integral continuations of the section or portion 9" of the hinge stop-strip 9", and this same integral construction is present also in connection with the hinge stop-strip 10", which is extended to provide the chan-

nel stop-strip 9^x. Furthermore, the plates or pieces 7 and 6', with their integral closing and stops strips, in Fig. 3 may be formed as an extension of one of the hinge stop-strips on the main and swinging frames, and this is true also of the strip 3 of Fig. 1, which represents a part similar in action, arrangement, and association to the strip 3^a. As clearly shown in Fig. 11, it will be noticed that the stop-strips on the main frame are identically like those of the swinging frame, being merely reversed to permit of the swinging of the inner frame.

Figs. 7 and 8 illustrate the hinge stop-strips of a frame swinging around vertically-disposed pivots, and the latter figure shows the preferred form of pivot or hinge, consisting of a socket 15, secured by screws passing through its flanges 16 into a part of the main frame 20 and the trunnion 17, secured to the swinging part of the window. This arrangement may, however, be reversed; but in either case the parts can be readily assembled and secured in position. For instance, the trunnion 25 may be secured to the swinging frame and the socket placed on this trunnion before the swinging frame is placed within the main frame, and then the assembled parts are slid into place within the main frame with the 30 socket resting therein, after which by securing the socket in place the connection is completed.

Fig. 10 illustrates the independent arrangement of the hinge stop-strip and the pivot connection for windows, in which the swinging frame is horizontally pivoted. In this form 35 18 is the socket, and 19 the trunnion, to be secured by its flange 20 to the swinging frame.

Referring to Figs. 5 and 6, it will be seen 40 that the two sashes are balanced by means maintaining a constant and effective balancing connection with both—that is to say, each sash is provided with a rack 18'—and these mesh with an intermediate pinion 19', so that one 45 sash balances the other and the balancing action will not be affected when the swinging frame is reversed, but will be maintained and constant in all the positions of the swinging frame. This pinion is journaled in a block 20', 50 which is held by screws 21 in a cut-out portion of the hollow parting-bead 22, as shown in Fig. 5^a, where it will be seen that the block has recesses 23 on its sides, receiving the flanges of the parting-bead.

55 One feature of our present arrangement is that the lower sash can be raised without lowering the upper to such an extent as to open the window at the top. For this purpose we extend the hollow parting-bead across the top 60 of the main frame and project this down into the window-opening sufficiently far to prevent an opening being left here when the lower sash is raised, say, to the point shown in Fig. 4.

We provide means whereby the swinging 65 or secondary frame may be weighted, so that

an accurate balancing of the said frame on its pivots may be obtained. For this purpose we provide a weight-box composed of iron pieces 24 25, Fig. 14, held by a part of the swinging frame and arranged to receive between them 70 the weight-sections 26. This box is closed by a plate 27, held in place by the screws 28. By placing more or less of these weight-sections in the box the frame may be accurately poised. This weight-box is placed in the hollow of the 75 central parting bead or strip 22, the pieces 24 and 25 being secured to the inner wall of the said parting-strip. There may be but one weight-box placed in the upper or lower part of the swinging frame, or two of them may be 80 placed in one side of the frame, one at the top and the other at the bottom, or four of them can be arranged on the swinging frame, two at the top and adjacent each other and two at the bottom, likewise adjacent each other. We 85 also provide weight-boxes 29, Figs. 4 and 13, in the sashes, so that by removing the cover-strip 30 more or less of the weight-sections 31 may be placed in the box, as shown in Fig. 13, and in this way an accurate balance may be 90 secured as between the two sashes.

Where we use the term "window" herein we do so in a generic sense without regard to the shape of the window, and meaning also any equivalent of a window construction. For instance, the hinge stop-strips and the closing-strips of our invention can equally as well be applied to an oval or round window, wherein the sliding sash are dispensed with, or our entire invention can be applied to that form of 100 window having a rectangular sash at the bottom and a half-round sash at the top. We do not limit our invention to any special form or shape of window to which it can be applied.

It is the preferred form of construction to 105 attach the hinged closing-strip slidably to the swinging frame; but we do not wish to be limited to this construction, as the same results may be obtained by attaching it slidably to the main frame and pivoting it to the swinging frame.

As seen in Fig. 4, screens 35 can be applied to the swinging frame 2 in any suitable manner. In the present instance that part of swinging frame on the outside of central parting-bead is made to extend far enough to allow the channel 36 to be secured thereto and permit one of the screens 35 to slide between the channel and end retaining-strip 37, while the other screen slides within the channel. 120 The outer sash is then guided between the channel and central parting-bead.

While it is preferable to employ two screens, yet it is obvious that but one screen, covering both sashes, will accomplish the necessary results, and in this respect we would ask that our invention be construed broadly.

We claim—

1. In combination in a window construction, with a main frame, a swinging frame therein, 130

high and low stop-strips on each side of the pivots and between the swinging and main frames and closing-strips pivotally supported and moving with the swinging frame, substantially as described.

2. In combination in a window construction with a main frame, a swinging frame therein, closing-strips pivotally connected to one frame and having a sliding connection with the other frame, said closing-strips lying between the side edge of the swinging frame and the inner side of the main frame, substantially as described.

3. In combination in a window construction with a main frame, a swinging frame therein pivotally supported, and closing-strips pivotally connected to the main frame to one side of the axis of the pivots of the swinging frame and lying over the space between the side edge of the swinging frame and the main frame, and a connection between the closing-strips and the swinging frame, substantially as described.

4. In combination in a window construction with a main frame, a secondary frame pivotally supported therein, high and low stop-strips on each side of the pivots and between the swinging and main frame, fixed closing-strips extending part way about one of the frames and ending near the pivots and pivotally connected closing-strips on one of the frames connected with the other frame, substantially as described.

5. In combination in a window construction, a main frame, a secondary frame pivotally supported therein and closing-strips angular in cross-section pivoted to one frame and arranged to lie between the main and secondary frame, substantially as described.

6. In combination in a window construction, a main frame, a secondary frame pivoted therein, closing-strips angular in cross-section, having one flange lying along the side edge of the secondary frame and the other flange closing the space between the main and secondary frames and a sliding connection between the closing-strips and the swinging frame, substantially as described.

7. In combination in a window construction, a main frame, a secondary frame swinging therein, a fixed closing-strip and a closing-strip moving with the swinging frame pivoted to the fixed closing-strip, and having a sliding connection with the side face of the swinging frame, substantially as described.

8. In combination in a window construction, a main frame, a secondary frame pivoted or hinged in the main frame, and a pair of high and low coacting stop-strips on each side of the pivot, one of said stop-strips on each side of the pivot being provided with a closing strip or flange to cover the space between the frame and the other stop-strip.

9. In combination in a window construction, a main frame, a secondary frame pivoted or

hinged in the main frame and a pair of coacting stop-strips, one of which is of substantially U shape in cross-section having a flange to coact with the opposing stop-strip and having also a closing flange or strip, substantially as described.

10. In combination in a window construction, a main frame, a secondary frame pivoted or hinged therein and a pair of hinge stop-strips each extending on opposite sides of the pivot, and each comprising a high and low part of substantially U shape in cross-section, the channels of the high and low parts of the same strip facing in opposite directions, said stop-strips being arranged so that the low part of one can override the low part of the other when the secondary frame makes a half-revolution, substantially as described.

11. In a window construction, the combination of a main frame, a secondary frame pivoted or hinged therein, a pair of stop-strips each extending on opposite sides of the pivot, and each being made up of a high and low part, each high part having formed therewith a flange to coact with the low part of the other strip and also a second flange closing the groove or space between the low part and the frame, substantially as described.

12. In combination in a window construction, a main frame, a secondary frame pivoted or hinged therein, and a pair of coacting stop-strips, one having two flanges extending at right angles to each other, one of which coacts with the other stop-strip and the second flange serving to close the space between said other stop-strip and the frame, substantially as described.

13. In combination in a window construction, a main frame, a secondary frame, pivots connecting the same with the main frame and a pair of hinge stop-strips at each pivot, said stop-strips being arranged independent of the pivots, substantially as described.

14. In combination in a window construction, a main frame, a secondary frame pivoted or hinged in the main frame, and hinge stop-strips each consisting of a high part and a separately-formed low part secured thereto, substantially as described.

15. In combination in a window construction, a main frame, a secondary frame pivoted or hinged in the main frame, and hinge stop-strips each formed of channeled material with a high and low part, and means connecting them consisting of a block to which each is riveted, said block being of angular form and fitting in the channels of the said high and low parts substantially as described.

16. In combination in a window construction, a main frame, a secondary frame therein, pivotal connections between the secondary and main frame, stop-strips extending along the sides adjacent the pivots and comprising high and low parts and stop-strips for the other

- sides of the frames comprising extensions of the hinge stop-strips, substantially as described.
17. In combination with a main frame, a swinging frame, hinge stop-strips having extensions at right angles to the main portions thereof, one of said extensions having a closing-strip on one edge and a stop-strip on the other, and the extension on the other hinge stop-strip coacting with the stop-strip on the extension first mentioned, substantially as described.
18. In combination with a main frame, a secondary frame, a hollow parting-bead on the secondary frame, a pair of sashes sliding in the secondary frame, racks on the sashes, a toothed wheel with which the sashes engage and a block secured in a cut-out portion of the hollow parting-bead and carrying the journal of the toothed wheel.
19. In combination in a window construction, a main frame, a secondary frame pivoted therein, sashes carried by the secondary frame and means for weighting the secondary frame to secure a perfect balance, substantially as described.
20. In combination in a window construction, a main frame, a secondary frame pivoted therein, sashes carried by the secondary frame and adjustable means for weighting the secondary frame to secure a perfect balance, said means comprising a weight-box with weight-sections arranged therein, substantially as described.
21. In window constructions, the combination of a main frame, a secondary frame pivoted therein, and having a hollow parting-bead, sashes arranged to slide on opposite sides of the said parting-bead and adjustable weight-sections arranged in the hollow parting-bead, substantially as described.
22. In window constructions, the combination of a main frame, a secondary frame pivoted therein, and having a hollow parting-bead, sashes arranged to slide on opposite sides of the said parting-bead and adjustable weight-sections arranged in the hollow parting-bead, substantially as described.
23. In combination, a main frame, a swinging frame therein having a hollow parting-bead, sashes sliding on opposite sides of the said parting-bead, bars held in the said parting-bead with a space between them, weight-sections arranged in the box thus formed, and a removable cover for the said box, substantially as described.
24. In combination, a main frame, a pair of sashes carried thereby, balancing means for the sashes and means for increasing or decreasing the weight of one sash, substantially as described.
25. In combination, a pair of sashes balancing each other and means for increasing or decreasing the weight of one of said sashes.
26. In combination, a frame, a pair of sashes carried thereby, balancing means for the sashes and means for increasing or decreasing the weight of either sash, said means consisting of a weight-box with weight-sections therein, substantially as described.
27. In combination in a window construction, a main frame, a secondary frame pivoted or hinged in the main frame and hinge stop-strips of substantially U shape in cross-section and arranged so that the flanges on one will enter the channel in the opposing strip and packing material in the said channel.
